UNITED STATES PATENT OFFICE.

MARSELIUS T. ASHE, OF CHICAGO, ILLINOIS.

PAPER-VENDING MACHINE.

Application filed December 31, 1924. Serial No. 759,038.

This invention relates to paper vending machines, and has for its object to provide a new and improved machine of this description, particularly adapted to vend newspapers, periodicals and the like. The invention has as a further object to provide a mechanism for discharging from a suitable receptacle a large, flexible device such as a newspaper or periodical, when the proper coin, or coins, are inserted in the machine.

The invention has other objects which are more particularly pointed out in the accompanying description.

15 Referring now to the drawings:

Fig. 1 is a front view showing a device embodying one form of the invention.

Fig. 2 is a sectional view taken on line 2—2 of Fig. 1.

20 Fig. 3 is a view showing one form of mechanism for discharging papers.

Like numerals refer to like parts throughout the several figures.

In carrying out the invention I provide a suitable casing 1, in which the papers are placed. This casing may have a cover 2, preferably hinged at 3, which may be taken off or opened to insert the papers, the cover being locked after the papers are inserted 25 by any suitable locking device, such as the lock 4 passing through a rotating eye 5, which passes through a slot in the cover 2. Located in the casing 1 is a part 6, engaged by the edges of the papers 7. If, for example, 30 newspapers are to be vended the newspapers are preferably folded in the manner they are now usually supplied to the public, and the folded edge is placed against the part 6. The face of the outer paper engages the wall 8 of the casing, and is preferably forced tightly thereagainst. This wall is preferably provided with an aperture having a transparent cover 9, so that the purchaser can see when the papers are 35 exhausted. Some suitable means is provided for forcing the papers toward the wall 8. Any suitable means for this purpose may be used. I have illustrated one construction for that purpose, which consists of a spring 40 pressed member 10, which engages the face of the last paper and which presses all of the papers toward the wall 8, the arrangement being such that, when one paper is discharged, the next paper is forced against 45 the wall 8. The spring may be arranged in

any desired manner. As herein shown there are two pivoted members 11 and 12, the member 11 being pivoted at 13 and the member 12 being pivoted at 14. A spring 15 is attached to the bottom of the member 11, 60 and the top of the member 12, the attachment at the top of the member 12 being such that the spring may be disengaged therefrom, when it is desired to fill the casing with papers, so as to take the pressure off 65 of the papers during the filling process. There are preferably two sets of the pivoted members 11 and 12, properly spaced apart, and two springs 15, connected therewith.

The wall 8 of the casing is arranged to 70 have a recess 16. This recess may be produced in any desired manner, as by providing the wall with the bent portion 17. A discharge opening 18 is provided, through which the papers are discharged one at a 75 time. The recess 16 is arranged to permit a portion of the paper to be bent as the end is lifted so that the end of the paper to be discharged will be moved beyond the edge 19 of the wall 20 of the casing. Some suitable means is provided for lifting the edge 80 of the paper to be discharged, when the proper coin is placed in the slot. In the construction shown there is provided a movable engaging part 21, which is provided with means for moving it to move the edge 85 of the paper beyond the edge 19 of the wall 20. As herein shown this mechanism comprises a pivoted member 22, which is connected with the member 21, which is pivoted at 23. A second pivoted member 24 is pivoted at 25 and is connected by a connecting piece 26 with the actuating part 27^a 90 outside of the casing, so that the end of the pivoted member 24 is moved toward the 95 member 22, when the actuating part 27 is moved, the actuating part being returned to its initial position when released by a spring 28.

The coin 29 is engaged between the actuating part 27 and the unlocking part 30, the coin passing through the shoot 31 to its position between these parts, see Fig. 2. Associated with the unlocking part is a locking device 32, provided with a projection 33, 100 which normally engages the unlocking part 30. This unlocking part has a notch 34, arranged so that when it is moved by the coin 29, the notch comes opposite the projection 33, and a spring 35 connected with the lock 105 110

ing part 32 moves said locking part in the direction of the arrow, the projection 31 entering the notch 34.

The unlocking device 30 is returned to its 5 normal position by a spring 36, when the coin is discharged, and the inclined portion 37 on the edge of the notch engages the projection 33 and causes the locking part 32 to move in a direction opposite to that of the 10 arrow and back to its initial position.

Some means is provided for connecting the members 24 and 22 when the coin is in position. The construction for this purpose illustrated in this drawing consists of the 15 connecting piece 38, pivoted at 39 to the member 22, and engaging a projection 40 on the locking device 32. This connecting piece 38 has a shoulder 41, and the parts are so arranged that when the locking device 32 20 is moved in the direction of the arrow the connecting piece 38 will also be moved by the projection 40, until the shoulder 41 moves to a position to be engaged by the member 24. The downward movement of 25 the member 24 then moves the connecting piece 38 and the member 22, so as to move the engaging part 21. This engaging part 21 normally extends part way along the papers, that is, so as to partially overlap them, 30 as illustrated, and also extends crosswise along the papers, preferably the full length thereof.

When the engaging device 21 is moved by the member 22, it moves along the wall 35 20, until its edge reaches a position where it does not engage the face of the paper, whereupon the spring pressed member 10 moves the bottom of all of the papers over toward the wall 20, so that the paper to be 40 delivered comes in alignment with the engaging device 21, said engaging device being ready to engage the lower edge of the paper and move it so that it will pass through the discharge opening 18.

45 When the locking member 32 moves back to its initial position the connecting piece 38 disconnects the members 22, and 24, and a spring 42, connected with the member 22, moves said member and the engaging device 50 21, so that the engaging device moves the paper to be discharged, so that its edge is beyond the edge 19 of the wall 20. This movement of the engaging device 21 bends a portion of the paper to be discharged, so 55 that it is received in the recess 16, as illustrated in dotted lines in Fig. 2, and when the edge of the paper gets beyond the edge 19 of the wall 20 it slides off of the engaging device 21, and straightens out its edge, then 60 passing through the discharge opening 18 and being exposed to view, so that the purchaser can take hold of it and pull it out of the case, whereupon the spring pressed member 10 moves the rest of the papers over, 65 so that the next one engages the wall 8.

The engaging device 21 is preferably provided with a beveled edge 43 to insure the edge of the paper slipping off of the engaging device 21, as above set out.

When another coin is placed in position 70 the operation above described is repeated.

It is desirable that the spring pressed member 10 be pressed against the papers with such force that they are pressed against the wall 8 with sufficient force to prevent 75 the paper engaged by the engaging device 21 from sliding along the wall 8, thus insuring the bending of the end of said paper so that it will be passed through the discharge opening 18 to be in the view of the 80 purchaser.

The engaging device 21 is preferably provided with two members 22 and two retracting springs 42, the retracting springs 42 bringing it back to its initial position, 85 as shown in full lines in Fig. 2.

It will thus be seen that newspapers, magazines, periodicals and the like may be vended by means of this machine by simply putting the proper coin therein. The 90 spring pressed part 10 preferably has associated therewith opposite the transparent part 9, some words, such as the word "Empty", so that the purchaser can see 95 there are no more papers in the casing.

I claim:

1. A paper vending machine comprising an enclosing casing adapted to receive the papers to be vended, said casing provided with a wall against which the paper to be discharged is pressed, a spring pressed member, which presses the papers toward said wall, said wall being provided with a recess, an engaging device for engaging the paper so as to bend a portion thereof into said recess, said engaging device arranged so that the edge of the paper is disengaged therefrom when it is moved a predetermined amount, the casing having a discharge opening in proximity to said engaging device through which the edge of the paper passes when it is released from the engaging device. 100 105 110

2. A paper vending machine comprising an enclosing casing adapted to receive the papers to be vended, said casing provided with a discharge opening, a wall against which the paper to be discharged is pressed, a spring pressed member, which presses the papers towards said wall, said wall being provided with a curved portion above said discharge opening, an engaging device for engaging the paper so as to bend a portion thereof into said curved portion, said engaging device arranged so that the edge of the paper is disengaged therefrom when it is moved a predetermined amount, the casing having a discharge opening in proximity to said engaging device through which the edge of the paper passes when it is released from the engaging device. 115 120 125 130

3. A paper vending machine comprising an enclosing casing adapted to receive the papers to be vended so that they are supported on their edges, said casing provided with a discharge opening, means for moving a portion of the paper to be discharged out of alignment with the remaining portion of the paper, and then releasing it, the straightening out of the paper when released, forcing the edge thereof through said discharge opening, so that the purchaser may withdraw the paper from the casing.

4. A paper vending machine comprising an enclosing casing adapted to receive the papers to be vended, said casing being pro-

vided with a discharge opening, means for holding one edge of the paper to be discharged and lifting the opposite edge thereof so as to bend said paper and release it so that said paper is exposed through said discharge opening, said means comprising an engaging device which engages the edge of the paper, an actuating part accessible from the exterior of the casing, and means for operatively connecting said actuating part and engaging part.

Signed at Chicago, county of Cook and State of Illinois, this 15th day of December, 1924.

MARSELIUS T. ASHE.
